UNITED STATES PATENT OFFICE.

JOSEPH T. AUGER, OF MINNEAPOLIS, MINNESOTA, ASSIGNOR OF ONE-THIRD TO E. O. VOYER AND ONE-THIRD TO R. H. MONAHAN, BOTH OF MINNEAPOLIS, MINNESOTA.

SHEET MATERIAL FOR CONSTRUCTION PURPOSES.

Application filed April 30, 1928. Serial No. 274,128.

My invention relates to sheet material for construction purposes and while not limited in regard to kind of material, I consider it particularly applicable to sheet metal. An object of the invention is to provide the sheet material with a plurality of corrugations so arranged as to greatly strengthen the material both lengthwise and crosswise. The sheet material is made in the form of plates of a size convenient for handling and for many purposes a plurality of these sheets or plates may be joined together at their edges by an overlap secured in place in suitable manner as by welding, riveting, bolting, etc. The joints will preferably be welded together in order to make them airtight and liquid tight when the plates are put together in such manner as to produce articles such as gas tanks, oil tanks, culverts, round or otherwise, water-pipes, water tanks, and other liquid holding tanks as well as tanks or bins for holding flour and other powdered substances. The sheet material may be employed for roofing either in flat, round, or curved condition. Riveting or bolting if found more convenient may be employed for producing forms for concrete work and sheeting for barns, silos, cars, sheeting for airplanes, and frame work of all kinds.

The full objects and advantages of my invention will appear in connection with the detailed description thereof, and the novel features of my inventive idea will be particularly pointed out in the claims.

In the accompanying drawings which illustrate the application of my invention, Fig. 1 is a perspective view showing a portion of a plate and the abutting edge of an adjoining plate. Fig. 2 is an end view showing two plates butted together and the joint covered with an overlapping flat strip. Fig. 3 is an end view showing two plates with their edges overlapped. Fig. 4 is a perspective view showing two plates butted together and the joint covered with a corrugated strip. Fig. 5 is a plan view of a portion of a plate.

Referring to the construction shown in the drawings, the numeral 10 designates a plate, the left half of which is provided with a series of equally spaced corrugations 12 and the right half of which is provided with a series of equally spaced corrugations 14. These corrugations are inclined downwardly at an angle to the two opposite sides of the plate so that corresponding corrugations of the two side portions converge toward a median line. The angle of inclination of the corrugations is dependent upon whether or not it is desired that the plate shall have the same stiffness for both the longitudinal and transverse axes thereof. Except for the corrugations which are located in the two lower corners of the plate as shown in Fig. 1, the corrugations of the two side portions meet each other so as to form apices located in the median line of the plate. If the two sets of corrugations were caused to meet each other in the form of sharp apices, there would be a line of weakness coincident with the median line. Therefore, I round the apices and also preferably extend them a downward bulge or flare as indicated at 16 whereby the plate is strengthened lengthwise along the median line. In the form shown in Figs. 1 and 2, the two side margins of the plate are left with similarly placed flat portions as indicated at 18 so that different plates can be butted together and a flat strip 20 secured in suitable manner over the joint. In the form shown in Fig. 3, the butting edges of two adjacent sheets respectively are formed with flat portions 22 and 24, the latter extending out at a slightly higher position than the other so that the two flat portions may be overlapped and secured together. The two flat portions when properly secured together are given additional strength on account of the increased thickness of the material. In the form shown in Fig. 4, the corrugations extend entirely to the side edges of the plate, and in such case, the plates two of which are indicated by the character 10 are secured together by a strip 26 which is corrugated in such manner as to fit snugly upon the corrugations of the butted plates and cover the joint. This strip is welded or riveted to the butting edges. The bottom edges of one plate may be butted against the top edge of another plate and these two butting edges secured together by a similarly corrugated strip, it being noted from Fig. 1 that the corrugations at the top of a plate will match up with the corrugations at the bottom of another plate. The corrugations may be produced in flat plates in any suitable manner as by pressing them between upper and lower dies.

I claim:

1. Sheet material for construction purposes comprising a plate having corrugations

formed diagonally therein so as to converge toward the middle line of the plate, corresponding corrugations merging into each other at said middle line by means of rounded apices.

2. Sheet material for construction purposes comprising a plate having corrugations formed diagonally therein so as to converge toward the middle line of the plate with corresponding corrugations merging into each other at said middle line by means of rounded elongated apices.

3. Sheet material for construction purposes comprising a plate having corrugations formed diagonally therein so as to converge toward the middle line of the plate, corresponding corrugations merging into each other at said middle line by means of rounded apices, and the opposite sides of said plate having flat margins.

4. Sheet material for construction purposes comprising a plurality of juxtaposed plates, each of which has corrugations formed diagonally therein so as to converge toward the middle line of the plate, corresponding corrugations merging into each other by means

of rounded apices, and an overlap for the adjacent edges of said plates.

5. Sheet material for construction purposes comprising a plurality of juxtaposed plates, each of which has corrugations formed diagonally therein so as to converge toward the middle line of the plate, corresponding corrugations merging into each other by means of rounded apices, the adjacent edges of said plates butting against each other, and a strip lapped over said butting edges.

6. Sheet material for construction purposes comprising a plurality of juxtaposed plates, each of which has corrugations formed diagonally therein so as to converge toward the middle line of the plate, corresponding corrugations merging into each other by means of rounded apices, the adjacent edges of said plates butting against each other, and a strip lapped over said butting edges, said strip being corrugated to fit snugly upon the corrugations of the plates.

In testimony whereof I hereunto affix my signature.

JOSEPH T. AUGER.
